DESIGN FOR A LADY'S BELT OR SIMILAR ARTICLE

Joseph Levine, New York, N. Y.

Application October 14, 1936, Serial No. 65,302

Term of patent 3½ years

To all whom it may concern:

Be it known that I, Joseph Levine, a citizen of the United States, residing in the Borough of Manhattan, city, county, and State of New York, have invented a new, original, and ornamental Design for a Lady's Belt or Similar Article, of which the following is a specification, reference being had to the accompanying drawing, forming a part thereof, in which the figure is a perspective view of a lady's belt or similar article, showing my new design, the essential feature of which is the rosette-like element of ornamentation.

I claim:

The ornamental design for a lady's belt or similar article as shown and described.

JOSEPH LEVINE.
